CLAIM

The ornamental design for a bottle, as shown and described.

DESCRIPTION

FIG. 1 is a right side view of a bottle showing our new design;

FIG. 2 is a rear view of the bottle;

FIG. 3 is a top view of the bottle;

FIG. 4 is a left side view of the bottle;

FIG. 5 is a front view of the bottle;

FIG. 6 is a first top perspective view of the bottle;

FIG. 7 is a first bottom perspective view of the bottle;

FIG. 8 is a second bottom perspective view of the bottle;

FIG. 9 is a second top perspective view of the bottle; and,

FIG. 10 is a bottom view of the bottle.

1 Claim, 4 Drawing Sheets(56)
